UNITED STATES PATENT OFFICE.

VICENTE C. SANTOS, OF SINGALONG, MANILA, PHILIPPINE ISLANDS.

SHOE-FASTENER.

1,353,424.

Specification of Letters Patent. Patented Sept. 21, 1920.

Application filed October 4, 1919. Serial No. 328,370.

To all whom it may concern:

Be it known that I, VICENTE C. SANTOS, citizen of the Philippine Islands, residing at Singalong, Manila, Philippine Islands, have invented new and useful Improvements in Shoe-Fasteners, of which the following is a specification.

This invention relates to improvements in shoe fastening devices, the object being to provide means by which a shoe may be easily and quickly fastened or unfastened.

A further object is the provision of a fastening device in which the degree to which the shoe is closed may be regulated, thereby providing for the convenience and comfort of the wearer.

Another object is to provide a device of the above character which may be operated by a single pull in an upward direction to fasten the shoe and a pull in a reverse direction to unfasten the same, provision being made for holding the device against accidental movement when the shoe is in fastened position.

Other objects and advantages of the invention will appear as the following description is read in connection with the accompanying drawings.

In the drawings;

Fig. 1 is a view of a fragmentary portion of a shoe equipped with an improved fastening device.

Fig. 2 is a similar view with the fastening device removed.

Fig. 3 is a detail perspective view of the fastening device.

Fig. 4 is an enlarged sectional view on the line 4—4 of Fig. 1.

Fig. 5 is a similar view on the line 5—5 of Fig. 1.

Fig. 6 is a detail view of the flexible tongue.

Fig. 7 is a similar view of one of the reinforcing members or plates.

Fig. 8 is a like view of the upper or securing plate.

Fig. 9 is a view similar to Fig. 1 illustrating the manner in which the invention may be used for fastening a shoe which is partly in opened position.

Referring to the drawings in detail, like characters of reference denote corresponding parts throughout the several views.

The invention may be applied to shoes of different characters, that is to both low and high shoes, but is illustrated in connection

with a low shoe of the "Oxford" type. The shoe is indicated at 10 and is opened along the central portion of the front after the manner of a lace-shoe, the opening being indicated at 11. This provides abutting edges which are adapted to be brought in contact when in closed position.

Arranged in rows adjacent each edge of the opening 11, are buttons or studs 12. These studs are equally spaced apart, being arranged in transversely aligned pairs. They are secured to the shoe, as shown at 13 and project beyond the front surface of the latter and are formed with a peripheral groove 14.

The buttons 12 are adapted for engagement by a flexible tongue 15, the latter being preferably formed of leather and having formed therein oppositely extending inclined slots 16, which are adapted to engage the peripheral groove 14 of the buttons, the said slots having at one end an enlarged entrance portion 17, through which the buttons may be passed to provide for removing and replacing the device, when desired. As shown in Fig. 6, the slots 16 are arranged in pairs, each pair being disposed at a different angle so as to provide for the shape of the portion of the shoe to which the device is applied.

Secured to the tongue 15 are reinforcing or stiffening plates 18, which are provided with slots 19, similar in shape and adapted to be positioned over the slots 16, for the passage or engagement with the buttons or studs 12. There is one plate for each opposite pair of slots, so that the tongue will be reinforced and stiffened at the point of engagement with the buttons, but will permit the tongue to retain a sufficient amount of flexibility for conformity to the shape of the shoe. The top of the tongue is provided with a plate 20, having openings 21 therein and is so spaced and shaped as to be positioned over slots 22 provided in the upper end of the tongue. The openings and slots 21 and 22 are arranged in oppositely extending diagonal rows and are adapted to receive buttons or studs 23, secured upon opposite sides and near the upper ends of the edges of the shoe opening 11. Both the plates 18 and 20 are longitudinally curved to conform to the curvature of the shoe. The lowermost plate 18 is provided with an up-turned end 24, which provides a finger-piece for a purpose herein-after apparent.

The device is removably positioned upon the shoe by passing the buttons 12 through the enlarged portion 17 of the slots, as shown in the drawings. By grasping the 5 plate 20 and pulling upward, the buttons will be moved toward one another, due to the inclination of the slots, the degree of movement being governed by the fit of the shoe. After the shoe has been properly adjusted, 10 the studs or buttons 23 are passed through the proper openings in the plate 20, whereupon the tongue will be held against longitudinal movement. To open the shoe the studs or buttons 23 are disengaged from the plate 20 and the tongue is pulled downward, or in a reverse direction 15 through the medium of the finger-piece 24.

The invention is susceptible of various changes in its form, proportions and minor 20 details of construction and the right is herein reserved to make such changes as properly fall within the scope of the appended claims.

Having described the invention, what is 25 claimed is:

1. A fastening device comprising buttons or studs arranged in spaced rows along the adjacent edges of an opening and means removably engageable with the buttons and 30 movable longitudinally of the rows, whereby the edges of the opening will be brought together or separated.

2. A fastening device for shoes comprising buttons or studs arranged in rows along 35 the adjacent edges of the shoe opening, means carried by the tongue of the shoe and engageable with the buttons and movable longitudinally of the rows for bringing together or separating the edges of the shoe 40 opening and means for holding the button engaging means against accidental movement.

3. A fastening device for shoes comprising buttons or studs arranged in rows along 45 the adjacent edges of the shoe opening, a slotted member engageable with horizontally aligned buttons on opposite sides of the shoe opening and movable longitudinally of the rows for bringing together or separating 50 the edges of the shoe opening and means for holding the button engaging means against accidental movement.

4. A fastening device for shoes comprising

ing buttons arranged in rows along the adjacent edges of the shoe opening, a flexible 55 reinforced slotted member engageable with the buttons and movable longitudinally of the rows for bringing together or separating the edges of the shoe opening and means for holding the button engaging means against 60 accidental movement.

5. A fastening device for shoes comprising buttons arranged in rows along the adjacent edges of the shoe opening, a reinforced flexible member having oppositely 65 arranged diagonal slots therein engageable with the buttons and movable longitudinally of the rows for bringing together or separating the edges of the shoe opening and means for holding the button engaging 70 means against accidental movement.

6. A fastening device for shoes comprising buttons arranged in rows along the adjacent edges of the shoe opening, a flexible tongue having oppositely extending diagonally disposed slots therein engageable with said buttons, separate reinforcing plates disposed transversely of the tongue, said plates having slots therein which register with the 80 slots of the tongue to provide surrounding reinforcing edges engageable with the buttons, whereby longitudinal movement of the tongue will open or close the shoe opening and means for holding the tongue against 85 accidental movement.

7. A fastening device for shoes comprising buttons arranged in rows along the adjacent edges of the shoe opening, a flexible tongue having oppositely extending diagonally disposed slots therein engageable with 90 said buttons, separate reinforcing plates disposed transversely of the tongue, said plates having pairs of slots therein which register with the slots of the tongue to provide surrounding reinforcing edges engageable with the buttons, whereby longitudinal movement of the tongue will open or close the shoe opening, a plate carried by the tongue and having transversely arranged slots 95 therein, said slots being arranged in rows and studs engageable with said slots for holding the tongue against accidental movement.

In testimony whereof I affix my signature.

VICENTE C. SANTOS.
